UNITED STATES PATENT OFFICE.

EDOUARD KELLER, OF BIENNE, SWITZERLAND, ASSIGNOR TO KELLER & GRÜRING-DUTOIT, OF SAME PLACE.

MACHINE FOR MAKING WATCH-CASES.

SPECIFICATION forming part of Letters Patent No. 366,778, dated July 19, 1887.

Application filed December 20, 1886. Serial No. 222,063. (No model.)

To all whom it may concern:

Be it known that I, EDOUARD KELLER, of Bienné, Switzerland, have invented an Improvement in Machines for Making Watch-Cases, of which the following is a specification.

My invention relates to mechanism for turning over the edge of a disk of metal, so as to give the blank the form suitable for being acted upon by dies that give it the finished shape of the watch-case. I accomplish this by means of grooved rolls supported in stocks fitted to slide radially in a stationary face plate, and said slides are moved gradually toward the center of the blank, thereby causing the grooved rolls to act upon the edge of the metal blank and roll over said edge as the blank is rotated, and give to said edge the same shape as the sectional shape of the groove of the rolls. The blank is clamped between heads while being rotated, and these heads are upon shafts on the same axial line, and they can be adjusted by screws to clamp the blank in the proper position for being acted upon by the rolls.

In the drawings, Figure 1 is a longitudinal section of the complete machine, with some of the parts in elevation. Fig. 2 is a front elevation, and Fig. 3 a rear elevation, of the face-plate and connected parts, the shaft being in section in Fig. 3. Fig. 3^a is a perspective view 30 of one of the stocks and its roll. Fig. 4 is an elevation in larger size, showing one of the grooved rolls as acting upon the blank, the latter being in section and clamped between the heads. Fig. 5 is an edge view of the blank 35 before being operated upon and a section of the blank with its edge turned over. Fig. 6 is a sectional elevation of the dies for giving to the blank its finished shape, as shown in this figure. Figs. 7, 8, and 9 are elevations and 40 sectional views of separate parts of the machine.

P is the base of the machine, upon which are the standards L L', having tubular bearings L² L'² for the shafts J J'. These shafts are upon the same axial line, and are rotated at the same speed by belts applied to the pulleys K K'. Said shafts J J' have heads k k', respectively, between which the blank of metal to form the watch-case is clamped, and these heads are each upon a short stud entering a hole in its 50 shaft, so as to be removable therefrom and al-

low of the use of different-sized heads in the same machine.

O O' are screws, with their inner plain ends entering the outer ends of the shafts J J', respectively, and N N' are nuts for rotating said screws and moving said shafts endwise, so as to firmly clamp the blank between the heads k k', and also to bring the blank to the proper position for being operated upon by the grooved rolls g. The inner end of the tubular bearing L² is reduced in diameter to receive the tubular hub a² of the face-plate A, and said plate and hub are keyed at l to said bearing, so as not to turn thereon. Upon the hub a² is the stock-mover B, having a circular range of teeth at B', and upon a cylindrical portion of B is the eye D of a lever, D', which latter carries a pawl, E, pivoted at F, that engages with the teeth B'. The nut C, screwed upon the end of the hub a², keeps the stock-mover B in place upon said hub a², and also the lever D' in place upon the hub of the stock-mover.

H are stocks fitted to slide in radial slots in the face-plate A, and upon the rear of each stock there are teeth b, entering a volute groove 75 formed in the face of the stock-mover B. The tools g, in the form of grooved rolls for acting upon the watch-case blank, are mounted in jaws G upon stems supported in the stocks H, and there are springs around said stems acting between the jaws and the stocks to allow the rolls to yield.

It will now be apparent upon reference to Figs. 2, 3, and 4 that by moving the lever D' back and forth the stock-mover B will be rotated through the pawl E and teeth B', and that the volute groove in B will act upon the teeth of the stocks H and cause said stocks and their rolls to be gradually moved toward the center of the face-plate, and that said rolls will gradually roll over the edge of the metal blank; and finally give it the same sectional shape as the sectional shape of the groove of the rolls, as illustrated in Fig. 4.

It is preferable that the heads k k' should be 95 of such a size as to clamp nearly all of the surface of the blank not acted upon by the rolls, so as to keep flat that part of the blank; and the head k' may form a stop to limit the operation of the rolls.

To remove the blank from between the heads it is first necessary to swing the pawl E to the position shown by dotted lines in Fig. 3. Then the lever D' is moved back and forth, which 5 rotates the stock-mover B in the reverse direction to that before described, and said stock-mover forces the stocks H away from the finished blank. When said rolls are clear of the 10 finished blank, the nuts N N' are rotated in the direction to draw the shafts J J' and their respective heads away from each other sufficient for the removal of the blank. The blank is now placed in the female die R and the male die Q q brought down to give the proper shape 15 to the watch-case; but my invention does not relate to this stamping operation.

I claim as my invention—

1. The combination, with the shafts J J', heads k k', and bearings for said shafts, of the 20 face-plate A, secured to one of said bearings, the stock-mover B upon a tubular portion of A, and having a circular range of teeth and a volute groove, the lever D', and pawl E, the stocks H, fitted to slide in the face-plate A, and 25 having teeth entering the volute on B, and the rolls g, mounted in said stocks H, substantially as and for the purposes specified.

2. The shafts J J' upon the same axial line, bearings for said shafts, heads upon the inner ends of said shafts, screws O O', and nuts N N', 30 for moving said shafts endwise, in combination with the face-plate secured to one of the bearings, the stock-mover B, with its circular range of teeth and volute groove, the lever D', and pawl E, the stocks H, fitted to slide in the face-plate A, and having teeth entering the volute on B, and the rolls g, mounted on said stocks H, as set forth.

3. The combination, with the two clamping heads for clamping and rotating the sheet-metal watch-case blank, of rolls grooved to correspond to the turned-over edge of the metal, stocks to carry the rolls, and mechanism for moving the rollers simultaneously toward or away from the revolving blank, substantially as set forth.

Signed by me this 20th day of July, 1886.

EDOUARD KELLER.
